UNITED STATES PATENT OFFICE.

BERT H. HORN, OF RICHMOND, INDIANA, ASSIGNOR OF ONE-HALF TO GILBERT R. MITCHELL, OF RICHMOND, INDIANA.

FREE-END-PAPER-ROLL HOLDER AND CUTTER.

1,161,862.

Specification of Letters Patent. Patented Nov. 30, 1915.

Application filed January 21, 1915. Serial No. 3,620.

To all whom it may concern:

Be it known that I, BERT H. HORN, a citizen of the United States, residing in the city of Richmond, in the county of Wayne and State of Indiana, have invented a new and useful Free-End-Paper-Roll Holder and Cutter, of which the following is a full, clear, and comprehensive specification and exposition, the same being such as will enable others to make and use the same with absolute exactitude.

The particular object of this invention is to provide distinctive improvements in the ordinary paper roll holder and cutter, whereby after removing a section of paper there will be left a free end of paper which one may easily grasp when desiring to remove another section of paper from the roll.

My object, broadly speaking, is to provide a construction of the character set forth which will be neat and attractive in appearance, strong and durable in construction, easily operated and controlled, and which can be manufactured and sold at a comparatively low price. And, finally, my object is to provide a paper roll holder and cutter in which the mechanism is adapted to adjust itself to rolls of various or varying diameters, from which the paper can be easily removed and severed in a neat manner without waste of paper, and in which a free end will always be left to be grasped when desiring to remove another section of paper from the roll.

Various other objects and advantages will suggest themselves as pertaining to this invention by an inspection of the following description in connection with the accompanying drawings.

The preferred means for carrying out my invention in a practical manner is shown in the accompanying drawings, in which—

Figure 1 is a front elevation of the invention. Fig. 2 is a top plan of the invention. Fig. 3 is an end elevation of the invention. Fig. 4 is a vertical cross section, as taken on the line 4—4 of Fig. 1. And Fig. 5 is a perspective detail view of one end portion of the operative mechanism.

Similar indices denote like parts throughout the several views.

In order that the construction, the operation, and the advantages of my invention may be more fully understood and appreciated I will now take up a detailed descrip-

tion thereof in which I will set forth the invention as briefly and as comprehensively as I may.

In the drawings the letters A and B denote the two base-members, which are adapted to be secured to a counter or the like. Connecting the base members is the bar C, and extending up from the members A and B are the respective standards D and E. Connecting the upper ends of the standards is the top-rail F. Revolvably mounted between the central portions of the standards is the shaft G, which carries therearound, in the usual manner, the roll of paper H, which has an outer free end I. Extending out forward, parallel with each other, from the standards D and E, are the channeled brackets 1 and 2, whose channels face inward toward each other, with carriage bearings therein.

Numerals 3 and 4 denote the two carriages, which are identical with each other, the same being adapted to slide forward and backward in the channels of the respective brackets 1 and 2. Extending across the rear end of the channel of each bracket is a pin, as the pin 5 shown in Fig. 3; and in each of the carriages is a hook, 6 and 7 respectively. Attached to and extending back from the hooks 6 and 7 and secured to the respective pins 5 are the respective helical springs 8 and 9, which tend to normally hold the carriages back to their limits of movement in that direction. Extending across between the central portions of the carriages 3 and 4, is the roller 10, which normally contacts with the periphery of the roll of paper, as shown in Figs. 2 and 4.

Carried by the lower forward portion of the carriages are the pivots 11 and 12, respectively, on which are pivoted the respective offset, or Z-shaped, hangers 13 and 14. Connecting the upper ends of the hangers 13 and 14 is the weight rod 15.

Numerical 16 denotes the guide-bar, which, preferably, is formed of sheet metal, with its ends turned back and pivoted to the lower rear corner portions of the hangers 13 and 14, by the pivot bolts 17 and 18, respectively, and over the forward face of the bar 16 the paper is adapted to travel as it is drawn from the roll.

Numerical 19 denotes the cutter-bar whose cutting edge is adapted to contact with the face of the guide-bar 16. The ends of the

- cutter-bar are secured to the brackets 20 and 21, the rear edges of the latter being parallel and near the face of the bar 16. The said brackets are pivoted to the hangers 5 13 and 14 by the respective pivots 22 and 23. In threading the device the end of the paper is first brought down back of the roller 10, and then between the bar 16 and the blade of the cutter bar 19.
- 10 When in normal position the several parts will stand in the position shown in Figs. 1 and 4. Then in order to remove a portion of paper one has only to grasp the projecting portion *h* and then pull forward, which 15 will first cause the hangers to swing on their pivots 11 and 12 to vertical position, as in Fig. 3. Then continuing to pull on the paper it will unwind from the roll *H*. Then without releasing one's pull on the paper the 20 withdrawn portion is first moved upward slightly, and then by applying more force to one edge than the other the paper will be severed, being cut by the edge of the bar 19. Then when the portion withdrawn is severed 25 it is apparent that the pull on the cutter will be released, thereby allowing the weight-rod 15 to swing the cutting mechanism back to the position shown in Fig. 4, thereby causing the bars 16 and 19 to move back, and as they 30 move back the paper will remain stationary thereby causing it to be projected below the bar 16 as in Fig. 4, the amount of projection *h* being substantially equal to the distance of movement of the bar 16 as it swings back.
- 35 By the above it is apparent that there is always provided a free end *h* for one to grasp who desires to remove paper from the roll.
- The springs 8 and 9 retain the roller 10 40 at all times in contact with the roll of paper *H*, making the cutting mechanism at all times in the same relative position to the roll of paper.
- It should be understood that by reason of 45 the pivotal arrangements of the cutter-bar and the guide-bar, with relation to each other, that the pull upon the paper in removing and severing it will automatically cause the edge of the cutter-bar to clamp the 50 paper upon the face of the guide-bar; and when the paper is released the edge of the cutter-bar will move away from the face of the guide-bar, thereby allowing the paper to pass freely between the edge of the cutter-bar and the face of the guide-bar.
- 55 It will be apparent that when in normal position, as in Fig. 4, the rear edge of the guide-bar 16 rests against the roll of paper, thereby acting as a guide for the paper to

direct it between the guide-bar and the cutter-bar, thereby making it easy to start a new roll in the device.

I desire that it be understood that various changes may be made in the several details of construction, from that herein shown and described, without departing from the spirit of my invention and without sacrificing any of the advantages thereof.

Having now fully shown and described my invention, what I claim and desire to 70 secure by Letters Patent of the United States, is—

1. A device of the nature set forth comprising standards, a roll of paper revolvably mounted between the standards, channeled 75 brackets extending forward from the standards, carriages slidably mounted in the brackets, a roller extending between the carriages, springs pulling rearward on the carriages and retaining the roller in contact with 80 the roll of paper, a hanger pivoted to each carriage, a weight-rod connecting the upper ends of the hangers, a guide-bar pivoted between the lower ends of the hangers, and a cutter-bar extending between said hangers 85 and located immediately above the guide-bar, all substantially as shown and described.

2. A free-end paper roll holder and cutter comprising vertical standards, means for 90 revolvably mounting a roll of paper between the standards, a bracket extending forward from each standard, a carriage slidably mounted to operate horizontally in each of said brackets, springs normally holding the 95 carriages to the rear, a roller extending between the carriages and held in contact with the periphery of the roll of paper by the said springs, hangers pivoted near their centers to the respective carriages, a rod connecting the upper ends of the hangers, a guide-bar pivotally mounted between the lower ends of the hangers, a cutter-bar extending between said hangers and located near said guide-bar, the swinging of the 100 hangers being adapted to cause the guide-bar and the cutter-bar to swing forward and backward as paper passes therebetween and is withdrawn and released by the operator, all substantially as shown and described. 110

In testimony whereof I have hereunto subscribed my name to this specification in the presence of two subscribing witnesses.

BERT H. HORN.
